198,763

BOTTLE

James E. Plummer, 2530 Beaufort Ave., Toledo, Ohio

Filed Feb. 14, 1964, Ser. No. 78,633

Term of patent 14 years

(Cl. D58—8)

FIG. 1

FIG. 2

FIG. 4

FIG. 4 is a perspective view of the end and rear opposite the end and front shown in FIGS. 1 and 2.

The dominant features of my design reside in the portions shown in full lines.

I claim:

The ornamental design for a bottle, substantially as shown and described.
